Anthony W. Jones, of New York N.Y. assignor to
Jas. McGregor Jr. — Letter, Patent No 408. Dated Sept 2nd 1851.
The schedule referred to in these Letters Patent and making part of the same
To all to whom these presents shall come:

I, the subscriber, that

I, Anthony W. Jones, of the city, county and state of New York, have invented or produced a new design for parlour stove plates and that the following is a full & clear description thereof, reference being had to the accompanying drawings, making part of this specification, in which figure 1, represents the top plate of the stove; figure 2, is a view of the removable top which covers the hole for the insertion of fuel; figure 3, is a view of the base plate; figure 4, a view of one of the feet; and figure 5, represents an urn which is placed on the top of the stove when set up.

The top plate (a) of the stove, see figure 1, is of an elliptical form, and has an interior moulding in the form of an ellipse, which is ornamented all around with a raised wreath of leaves (b), and at the extremities of the shortest diameter of the ellipse, and in

said wreath are two escutcheons (c, c') - the one (c) has for its emblem, a bird in the act of flying, and the other (c') which is placed between four leaves, two on each side and tied together under its base, is ornamented with a tree. At the extremities (d) of the longest diameter of the ellipse, the leaves forming the wreath are somewhat enlarged.

The exterior periphery of the top plate (a) is ornamented at each extremity of its longest diameter by a device representing doves (e, e, e, e') volante and in the act of plucking, at the same flower - the flower (f') being large & fully blown, and the other (f) resembling a small flower or bud.

At the ends of the shortest diameter of said top plate, a similar device to the one just described is represented except that the birds have crests and long tails, and resemble peacocks or birds of paradise; the intermediate portions of the periphery of said top plate, are decorated with foliage in order to complete the exterior border thereof. -

The removable top plate (g), see figure 2, is elaborately ornamented with leaves & flowers; it is of elliptical form, and at both extremities of its shorter axis are seen two cherubs (g) reclining in foliage; at one extremity of the longer axis is represented a bird (g) setting on a nest, and at the other a nest of young birds (s) in the act of being fed by the old bird (t) who is disturbed by the snake (t').

The base plate (w) of the stove, see figure 3, is cast with a Grecian border of cyma recta and cyma reversa ornaments and foliage around the short elliptical cylinder which receives the body of the stove; in the center of the front part of said border, is an ornament resembling an escutcheon.

The general outline of the base plate is rectangular with a projection (v) in the rear in which is

cast a short cylinder for the reception of the smoke pipe - it is ornamented entirely around with an inclined Roman border in which are four faces (w), one in front, one immediately in the rear of the smoke pipe, and the other two at the sides.

A view of one of the feet is seen in figure 4; it is ornamented on each side about half way up with cyma recta and cyma reversed (or ogee) curves, and in the centre is a vase (g') surmounted by a face (h) and on each side thereof the head of an animal, resembling a dog is represented. Each foot is cast with a projection at the top by which it is joined to the base plate.

The base of the . . . vase (y), by which the stove is surmounted when set up, is elliptical in form, to suit the centre of the removable stop plate (g) & is composed of scrolls (x) united at top by a Roman border (l'), immediately above which are four panels (m) slightly overhanging, each of which is ornamented with a lion's head (n).

The body of the vase is provided with handles which are ornamented in the ogee style, and on each side there is an escutcheon representing a warlike figure trampling on a crow, and armed men in the background. The vase is provided with a cover (o') ornamented with flutes (b) converging to its centre.

A rod passes up through the said cover (o') and has an ornamented knob or handle (c') and is secured under the top plate by a nut or otherwise.

I claim as my invention or production, and desire to secure by letters patent the above described & illustrated designs for the several plates of a stove, as fully set forth; that is to say, I claim the designs on each of the plates separately & on all the plates in combination.

A. P. Browne

A. W. Jones.
